UNITED STATES PATENT OFFICE

WILLIAM BANCROFT, OF PAWTUCKET, RHODE ISLAND

TENNIS RACKET FRAME

Application filed November 22, 1930. Serial No. 497,581.

The present invention relates to improvements in tennis rackets and has for an object to provide certain improvements over the prior Patent No. 1,156,340, granted Oct. 12, 5 1915, to Frederick J. Bancroft.

In that patent use was made of a rawhide strip interposed between the inner and outer strips of wood which go to form the bow and handle of a tennis racket. According to the 10 patent, the strip of rawhide was continued through the extent of the bow and for some distance into the handle. In dry climates the rawhide has had a tendency to shrink, thus pulling the top of the bow out of shape. This 15 distortion resulted either in a twisted bow or in a pulling over to one side of the entire top. The present invention is intended to overcome these disadvantages.

Another object of the invention is to 20 simplify the construction and to minimize its expense.

With the foregoing and other objects in view, the invention will be more particularly described hereinafter and more particularly 25 pointed out in the appended claims.

In the drawing, in which like parts are denoted by like or similar reference characters throughout the several views,

Figure 1 is a plan view of an improved tennis racket construction according to the present invention but with the net removed.

Figure 2 is a fragmentary plan view, taken on an enlarged scale, of a portion of the bow frame.

Figure 3 is a cross section taken on the line 3—3 of Fig. 2.

Figure 4 is also a section taken on the line 4—4, also in Fig. 2.

Referring more particularly to the drawing, 5 and 6 designate the inner and outer strips of wood which constitute the bow of a tennis racket. These strips also preferably extend into a handle 7. At 8 is indicated the throat piece or crotch located between the adjacent portions of the inner strip 5 where the same converges into the handle.

Now, in accordance with the invention, a strip of rawhide 9 is placed between the wooden strips 5 and 6, but only across the upper portion of the bow of the racket. Such raw-

hide strip 9 is supplemented by thin strips of black walnut 10 and 11. The outer ends of the black walnut strips 10 and 11 are spliced or otherwise secured to the opposite ends of the rawhide strip 9; while the inner 53 convergent ends of the black walnut strips 10 and 11 pass into the handle 7, maintaining their position between the strips 5 and 6.

The rawhide strip 9 and the black walnut strips 10 and 11 are preferably of the same 60 width as the wooden strips 5 and 6, and they are exposed upon opposite faces of the racket frame. The net, which has been omitted for clearness, may be utilized to secure the various strips together into a laminated structure.

Rawhide or other strips 12 and 13 may be applied to the exterior of the outer wooden strip 6 immediately beyond the throat 8 of the frame for compensating for strain at this 70 point. This construction is shown in the prior patent aforesaid. In such prior patent, it was proposed to place a reinforcing strip of rawhide across the throat piece, but I preferably employ a wooden strip 14 in its place. 75 In this way rawhide is removed from the inner lower portion of the bow frame and the rawhide strips 12 and 13 upon the exterior are of only comparatively short length and do not extend to the outer rawhide strip 9. 80

In Figures 3 and 4 are shown the openings 15 for the stringing of the racket.

In Figure 4 is shown a section taken through the top portion of the racket bow frame, illustrating the rawhide strip 9 interposed between the wooden frame strips 5 and 6.

In Figure 3 is shown a section taken through the racket frame at a point where the rawhide and black walnut strips are joined together. These strips are preferably mutually tapered whereby they may overlap through a great area of surface contact without increasing the width at any point. Glue or other fastening means may be employed 90 to secure the strips together throughout this extensive tapered or wedge surface. Also glue or other material or fastenings may be employed to secure the strips of wood to the strip of rawhide and the strips of black wal- 95

nut. The racket will be strung and finished in accordance with usual methods and standards.

6 The rawhide strip 9 will incorporate the necessary strength and toughness to the frame at a point most remote from the handle 7 and throat piece 8. The black walnut strips 10 and 11 form an unbroken link between this rawhide strip 9 and the handle 7, thus knitting the structure into a united whole. Externally the bow frame and handle will be reinforced at a point adjacent the handle by the rawhide strips 12 and 13. The black walnut strip has been found to resist shrinkage especially in dry climate and they have for this reason been utilized to replace the rawhide in the old structure throughout the sides of the bow and the handle. At the same time all of the advantages of the rawhide structure are retained at the outer portion of the bow where they are most needed. The black walnut wood is especially advantageous for the purpose, possessing a desirable toughness, durability and flexibility. It is easy to handle and obviates all of the disadvantages of the prior construction, while retaining all of the desired features.

Having thus described the invention, what is claimed as new is:

- 20 1. An improved tennis racket comprising a plurality of bow strips of wood, a strip of rawhide interposed between the wooden strips at the outer or top portion of the bow, and supplementary strips of black walnut or other appropriate substantially non-shrinkable material joined with the ends of the rawhide strip and lying between the strips of wood at the sides and lower portion of the bow frame.
- 25 2. An improved tennis racket comprising a plurality of bow strips of wood, a strip of rawhide interposed between the wooden strips at the outer portion only of the bow frame, black walnut or equivalent substantially non-shrinkable wooden strips extending in the sides and lower portion of the bow frame between the wooden strips and connected to opposite ends of the rawhide strip, and means for uniting all of the strips.
- 30 3. An improved tennis racket comprising a plurality of bow strips, a strip of rawhide interposed between the first named strips at the outer portion only of the bow, black walnut or equivalent substantially non-shrinkable strips spliced to the ends of the rawhide strip and forming continuations of the rawhide strip in the opposite sides and lower portion of the bow frame, said black walnut strips extending into the handle of the racket, and means for securing all of the strips together.
- 35 4. An improved tennis racket comprising inner and outer frame bow strips, a handle into which said strips extend, a relatively short length of rawhide extending across the

top portion only of the bow frame and lying between such inner and outer strips and secured thereto, the end portions of said rawhide strip being bevelled on a gentle bevel, two strips of black walnut or equivalent non-shrinkable material forming continuations of said rawhide strip and extending between the two first mentioned frame strips in the side portions and lower part of the bow and extending into the handle, said black walnut strips being bevelled at their outer portions on gentle bevels mating with the bevel ends of the rawhide strips, fastening means for securing the bevel portions of the rawhide strip and the black walnut strip together, and fastening means for securing all of the strips together.

5. An improved tennis racket comprising a bow portion and a handle, said bow portion composed of inner and outer strips forming an open frame, which strips extend into the handle, a strip of rawhide material extending across the top portion only of the bow frame between said strips, black walnut or other equivalent non-shrinkable strip secured to the ends of the rawhide strip and extending in the side portions at lower part of the bow frame, said black walnut strips also extending into and forming a part of the handle, a throat piece at the convergent ends of the inner frame strip, a wooden strip extending across said throat piece and up along the sides of the inner frame strip, and a rawhide strip applied to the exterior of the outer frame immediately adjacent the throat piece.

In testimony whereof I hereunto affix my signature.

WILLIAM BANCROFT.
